UNITED STATES PATENT OFFICE.

ROBERT H. F. SEWALL AND NICHOLAS H. SEWALL, OF SMITHLAND,
LOUISIANA.

UTILIZING EXHAUST-STEAM.

SPECIFICATION forming part of Letters Patent No. 372,713, dated November 8, 1887.

Application filed November 15, 1886. Serial No. 218,053. (No model.)

To all whom it may concern:

Be it known that we, ROBERT H. F. SEWALL and NICHOLAS H. SEWALL, of Smithland, Pointe Coupee parish, and State of Louisiana, 5 have invented a new and useful Improvement in Utilizing Exhaust-Steam, of which the following is a specification.

This invention is an improvement in steam-engines, whereby the exhaust-steam may be utilized; and it consists in certain features of construction and novel combinations of parts, as will be described and claimed.

In the drawings, Figure 1 shows the improvement in connection with a boiler and a steam-engine, and showing the improvements as adapted for utilizing only a part of the exhaust; and Fig. 2 is a detail view showing the improvement as adapted for utilizing all the exhaust.

20 The boiler A and engine B may be of any suitable construction. The cylinder b of the engine is connected by a pipe, C, with a supplemental cylinder, D, made usually, as shown, of less cross-sectional area than the engine-cylinder. Such pipe C receives the exhaust from the cylinder b and conducts the exhaust from such cylinder b to the supplemental cylinder D. The pipe C may open into the cylinder D, near one end thereof, as shown in Fig. 1, or 25 about midway its ends, as shown in Fig. 2.

A pipe, E, connects with the supplemental cylinder and serves as a channel, through which the exhaust-steam is directed in its passage to the boiler. In the construction shown the pipe 30 E leads into a blower, k, which is connected by pipe E' with the boiler; but while such blower is preferred it is manifest it might be omitted without departing from some of the broad principles of my invention.

35 The pipe E in Fig. 1 opens into the supplemental cylinder near one end thereof. In Fig. 2 the pipe E opens into the cylinder near one end, and has a branch, e, which opens into the end of cylinder opposite that into which the 40 main portion or stem of the pipe opens.

It will be noticed that the pipes E and C have check-valves 1, the operation of which will be understood from the drawings. The piston F operates in cylinder D, and has its stem f suitably supported, usually on a cross-head, G, as 45 shown.

To the piston, and preferably through the medium of its stem and the cross-head, is connected one end of a lever, H, pivoted between its ends, and having its other end connected with some moving part of the engine, preferably the cross-head, as shown in Fig. 1.

In operation it will be seen that the exhaust-steam is forced into the supplemental cylinder, and thence by the piston F back into the boiler. 55 Now it will be seen that the piston not only forces the exhaust toward or into the boiler, but produces a suction, which draws the exhaust into cylinder D and prevents any back-pressure on the engine-cylinder.

Now, while we prefer the lever H, connected and operating as shown, it is manifest that instead of such lever the piston of the supplemental cylinder might be run in direct line with the main shaft by means of an eccentric 60 similar to the construction for operating the common slide-valve.

In order to give the exhaust-steam proper force to enter the boiler A, and also to provide a means for, in part at least, feeding water to 65 said boiler A, we provide the pump I, which may be an ordinary steam-pump having a water-supply pipe, I'. From this pump a pipe, i, extends into the pipe E, and is provided with a nozzle, J, pointing in the direction of 70 the boiler A, forming an injector, which, by suction and direct action, gives the exhaust-steam an impetus in such direction, and also, by means of the jet of water, in part at least, 75 condenses such exhaust-steam. The pump I, 80 through pipe i, serves to inject a jet of cold water into the pipe E and forces the steam toward the boiler. In its passage between the pump I and the boiler A the steam and water pass through a pump, K, preferably of a rotary form, 85 as shown, which in practice is given a fast motion and operates to force the steam, &c., into the boiler.

Now it will be understood that, in addition to serving as a means for aiding in forcing exhaust-steam back into the boiler, the pipe E and pumps I and K may be used for forcing 90 back into the boiler steam which has been employed for boiling sugar or other material.

Having thus described our invention, what we claim as new is—

1. The combination of the boiler, the sup-

plemental cylinder and piston, the pipe C, leading from the boiler into the cylinder, the pipes E E', connecting said cylinder with the boiler, and the blower interposed between such pipes, substantially as described.

2. The combination of the engine, the main boiler, the supplemental cylinder, pipes connecting such cylinder with the engine and with the boiler, the piston in said cylinder, the pivoted lever connected at one end with the piston and at its opposite end with the engine, the pump I, and the pipe extended therefrom into

the pipe between the boiler and supplemental cylinder, substantially as set forth.

3. The combination, with the boiler A, of 15 the pipes E E', the piston-cylinder D', the pump K, the pump I, and the pipe i, leading from pump I into pipe E, substantially as set forth.

ROBERT H. F. SEWALL.
NICHOLAS H. SEWALL.
